UNITED STATES PATENT OFFICE

RAY W. ARMS, OF CHICAGO, ILLINOIS, ASSIGNOR TO ROBERTS & SCHAEFER COMPANY,
OF CHICAGO, ILLINOIS, A CORPORATION OF ILLINOIS

APPARATUS FOR CONTROLLING AIR IN DRY SEPARATING TABLES

Application filed January 30, 1928. Serial No. 24,834.

My invention relates to improvements in means for controlling and distributing air which is supplied to dry separating tables and has for one object to apply a new and 5 improved means for adjusting and controlling the air flow so as to insure a proper relation between the velocity of the air or gas current upon which a flowing sheet of finely divided material is partially floated as it 10 passes over a separating table. Another object of my invention is to provide means for adjusting the air or gas with a minimum of difficulty and delay so that an unskilled operator may make the necessary adjust- 15 ments to enable the table to satisfactorily handle different characters and quantities of material.

Experience shows that if the deck which carries the flowing stream or sheet of divided 20 material offers the same resistance to air flow throughout its entire area and if there are provided beneath the deck a series of manually adjustable shutters or baffles strips which can be set to control the air flow, that satisfac- 25 tory separating will take place. Experience further shows that these shutters or baffles are exceedingly sensitive and very slight changes beneath different parts of the deck may give rise to great differences in 30 operation and it is desirable to provide means for decreasing the sensitiveness of these shutters so that a relatively unskilled operator may still be able to make correct adjustments.

Experience also shows that where the 35 resistance to air flow afforded by the flowing sheet of material itself as distinguished from the resistance afforded by the deck is great, slight changes such as are always taking place in the character of the sheet of material as 40 for instance, the introduction of a flat piece of slate or the like may give rise to great differences in action. It is desirable therefore to have the resistance to air flow of the flowing sheet relatively small with respect to the total 45 resistance encountered by the sheet. In order to take care of these various situations I propose to build into the deck in addition to the normal pervious surface which carries the stream of material and through which the air 50 passes, a series of reciprocating elements con-

forming generally to the various parts of the deck surface, thus decreasing the total effect of change of the shutters and thereby making them less sensitive. In addition to this I propose to provide beneath the manually ad- 55 justed shutters a perforate plate or other suitable air flow resisting elements which will build up resistance to the air.

Experience shows that the resistance of the stream of coal or other material to air flow is approximately .3 inches water gauge. The resistance to flow of air afforded by the pervious surface of the deck itself is approximately .5 inches water gauge, thus the resistance without any additional resisting means of the coal sheet itself is a very large proportion of the total resistance. When I have the perforate plate beneath the deck it can be given a resistance to air flow of approxi- 60 mately .9 inches water gauge and we then get the resistance of the coal as related to the resistance of the total structure approximating in the proportions of one to three. When this is the case slight temporary variations in the character of the coal or other bed of material if separated is of relatively less consequence and therefore as such slight changes are continually taking place, the ad- 65 verse effect of these changes on the separator is reduced to a minimum.

Experience shows that in order to get the desired effect it is necessary to provide other means for distributing the air and I do this by feeding the air to the area beneath the perforate plate to an évasé chimney or gradually opening cone which more or less conforms to the cross sectional area of the table or deck and which therefore brings the air to the underside of the perforate plate in such manner that pressure beneath that plate is 70 substantially constant throughout the entire area thereof.

Experience also shows that at certain points on the deck where the sheet is fixed, it is desirable to provide means for increasing the supporting effect of the air. Under some conditions it is desirable to leave off the damping effect or perforate plate and also to provide means for bringing an increased quantity of air to the deck, the reason for this 75 80 85 90 95 100

being that in the zone immediately adjacent the point where material is fed to the deck and before any appreciable separation has taken place and before the sheet has had time to spread out, the sheet is of such thickness that the normal or supporting effect desirable in those parts of the deck removed from the supply is not sufficient and I therefore provide a partition in the évasé chimney 10 which may actually take the form of a reversed cone to concentrate rather than distribute the air flow and concentrate this air beneath that part of the sheet where it is at its maximum thickness.

15 My invention is illustrated more or less diagrammatically in the accompanying drawings, wherein

Figure 1 is a plan view;

Figure 2 is a plan view of the cone in section through the bermis cloth which joins the cone and deck;

Figure 3 is a section along the line 3—3 of Figure 1;

Figure 4 is a section along the line 4—4 of Figure 3.

Like parts are indicated by like characters throughout the specification and claims.

A is a supporting frame. From it project upwardly brackets A¹. A² is a reciprocating frame supported by a link A³ on a bearing A⁴ on the bracket A¹ and a link A⁵ on an adjustable slide A⁶ on the bracket A¹ whereby the angle of inclination of the frame A² may be adjusted. A⁷ is a drive link whereby the frame A² may be reciprocated on the pivot links A⁸ A⁹. A⁸ is a deck frame hinged on the frame A² along a line generally parallel with the line of reciprocation. A⁹ is an adjusting screw associated with a hand wheel A¹⁰ and a bearing A¹¹ on the frame A² whereby the frame A⁸ may be angularly adjusted about an axis at right angles to the adjustment axis of the frame A² and thus the inclination of the deck may be controlled both in a direction parallel with reciprocation and at right angles thereto.

B is a pervious deck of screen cloth or other suitable material mounted on the reciprocating slats B¹ in the frame A⁸. Mounted on these slats and adapted to control the space between them are manually adjusted shutters B² of tin or other suitable easily bent material. B³ B⁸ and B⁴ B⁴ are riffles extending longitudinally of the perforate deck in the direction of reciprocation. The riffles B⁸ nearest the feed end of the deck are higher than the riffles B⁴ further removed therefrom. The riffles B⁴ decrease in height above the deck in the direction of reciprocation away from the feed end of the deck. The riffles B³ are as above indicated much higher than the riffles B⁴ and stop short at a point slightly removed from the feed end of the deck and the riffles B⁴ continue at their normal height from the ends of the riffles B³. B⁵ is a chute

70 mounted on the frame discharging to the deck against the high riffles B³. This chute reciprocates with the deck and receives coal or other material from a fixed chute B⁶ so disposed that the two chutes are always in register independent of the reciprocation of the deck. The two side walls of the frame extending in both directions from the chute B⁵ as at B⁷ and B⁸ are higher than the maximum thickness of the bed so that there is never 75 at any time any discharge of the material over the walls B⁷ and B⁸. B⁹ is a guide wall inclined downwardly from the wall B⁸ at a point beyond the terminus of the high riffles. Coal does discharge over this wall onto an 80 impervious part of the deck at B¹⁰. From Figure 1 it will be noted that the pervious part of the deck does not extend to the upper right hand corner of the deck but there is an 85 impervious area B¹¹ so that the shape of the pervious portion of the deck is an irregular hexagon.

89 C is a refuse trough discharging into a refuse chute C¹. C² is a middlings trough discharging into a middlings chute C³. C⁴ C⁵ are coal troughs discharging into a coal chute C⁶. C⁷ C⁸ are extension plates bridging the gap between the deck and these troughs, and so arranged that they are always in register with the troughs independent of the reciprocation of the deck. C⁹ C¹⁰ are deflector blades movable along the plate C⁸ so disposed as to separate the middlings, the refuse and the coal as they pass over the deck extensions into the troughs.

100 D is an air supply duct leading from any suitable air supply not here shown. It discharges into an upwardly expanding évasé chimney D¹ mounted on the frame A and terminating in a discharge mouth D² underlying and of substantially the same shape and cross sectional area as the pervious part of the deck. D³ is a bermis cloth bellows bridging the gap between the mouth D² and the underside of the pervious deck. D⁴ is a funnel or collector mounted within the évasé chimney and upwardly decreasing in cross sectional area. An interior bellows D⁵ extends from the top of this deflector at D⁴ to the deck. Mounted within the frame A⁸ beneath the deck and out of contact with the manually adjustable shutters are a pair of perforate resistance plates D⁶ which plates are cut away beneath the high riffles so that the air passing in through the funnel D⁴ is discharged against the underside of the deck beneath the deck without interference. All the other air which is discharged against the underside of the deck except beneath the high riffles passes through the resistance plate. The bellows D⁵ constrains the air which enters through the funnel and discharges it directly against the underside of that part of the deck where the high riffles are located. 130

- The resistance to air flow furnished by the resistance plate is fixed once and for all when the apparatus is built but is such that the air flow resistance exerted by the flowing film or sheet of material as it passes over the deck is much less than the resistance to air flow set up by the resistance plate, the manually adjusted shutters and the previous deck itself.
- 10 Experience shows that if the internal resistance of the deck, that is,—the resistance of the deck and its associated parts, to air flow as distinguished from resistance to air flow of the material traveling across it is high, the expense of operation becomes extravagant because it is exceedingly expensive to pump air. On the other hand, experience shows that if the internal resistance is too low in proportion to the resistance of
- 15 the material, unsatisfactory operation results because slight changes in the thickness of the material bed or changes in the character of the material may radically increase or decrease the air resistance and cause difficulty in distribution. Our experience has been that if the internal resistance of the deck is less than five times the external resistance and not less than three times the external resistance, satisfactory operation results at an
- 20 expense which is not prohibitive.

It will be evident that while I have shown in my drawings an operative device, still many changes might be made in the size, shape, arrangement and disposition of parts 25 without departing materially from the spirit of my invention and I wish, therefore, that my showing be taken as in a sense diagrammatic.

- It is obvious that while I have suggested a preferred range of numerical relation between the internal resistance to the deck and the external resistance of the sheet of material flowing over it, nevertheless any range wherein the conical resistance was sufficiently 40 greater than the external resistance to make the deck in its operation essentially independent of temporary variations in flow is satisfactory. Under some conditions the internal resistance might be even less in proportion to 45 the external resistance than above stated or it might be much greater but in any event the internal resistance must be such that variation in the external resistance in operation bears such a relation to the total resistance 50 that such variation does not exert a deleterious effect. The benefit of this is that it makes it possible to design the equipment for a given set of conditions and install it with a minimum of adjustment in the field.
- 55 Since whatever adjustment is necessary must be made by skilled operators as a result of the long tedious cut and dried method under ordinary conditions anything that makes it possible or tends to make it possible to design 60 and build a plant and goes into operation

without special adjustment in the field is manifestly of the utmost importance.

The use and operation of my invention are as follows:

The engineer who installs the plant determines the dimensions once and for all. He 70 selects the type of resistance plate to be used and he bends the separate shutters to the proper angle to give a satisfactory distribution of the air throughout the entire surface. The operator may from time to time during 75 the operation change the angle of inclination in both directions of the deck. The dimensions of the riffles and the relation between them and the previous surface will not, however, be changed though the position of 80 the deflector blades dividing the coal, middlings and refuse discharge zones may be changed.

The machine is started and the deck is reciprocated. Coal is fed into the fixed chute, thence through the reciprocating chute onto the deck. The coal until it builds up above the high riffles is free to move only in a direction parallel with the direction of reciprocation. As soon as it builds up above the high 85 riffles, if it does, it can travel over them onto the other riffles. Normally the coal will follow the arrows in Figure 1 and because of the extreme height of the lowermost of the high 90 riffles little if any coal will get over. This gives a deep bed of coal and refuse and this deep bed is exposed to the action of the concentrated stream of air traveling in the direction of the arrows, X X in Figure 3. As soon as the coal or coal and refuse gets away from the high riffle zone, it spreads out as indicated by the arrows on Figure 1 and is subjected to 95 the influence of the air traveling in the direction of the arrows Y through the retarding plates. The refuse being heavier will stay beneath the riffles and travel in the direction 100 of the arrows Z Z in Figure 1. The coal being lighter will gravitate to the top of the sheet and travel across the riffles down toward the lower edge of the deck in Figure 1. The refuse together with some coal perhaps traveling out beyond the end of the riffles will move 105 in the direction of the arrows Q toward the refuse trough. The resistance furnished by the retarding plates is so great that slight variations in thickness or air retarding quality of the sheet away from the high riffle zone will not exert an appreciable 110 change on the air flow because no variation can be more than a comparatively small percent of the total air resistance. In the high riffle zone the bed is so thick that a piece of slate or a slight change in the character will 115 not appreciably effect the character or quantity of air resistance and therefore at all times the air distribution will remain substantially constant as set by the installation engineer when he initially sets up the apparatus. The air caught by the reverse funnel and dis-

charged to the high riffle zone will, of course, exert a greater lifting force than the air on the balance of the deck and this is necessary because it is desired in the thick bed held by 5 the high riffles to get quick support. This separation must be as accurate as the separation in the balance of the deck but the quick initial separation results in concentrating the material somewhat so as to permit more accurate separation on the balance of the deck.

10 It will be noted from Figure 4 that the riffle in the group of riffles furthest removed from the feeding means is substantially higher than any of the others. It will be noted that the resisting means, 15 that is,—the means which resists the air flow in addition to or separate from the resistance set up by the deck and the burden of material on the deck is formed by two perforate plates 20 D'; and that these plates are close together and that the distance between them is less than the distance between the uppermost of the two and the deck itself.

I claim:

25 1. In an air separating table, a pervious deck, means for reciprocating it, means for discharging air upwardly through it, riffles projecting upwardly from it, extending in the direction of reciprocation and decreasing 30 in height from one end to the other, means for feeding material to be treated to the deck and a plurality of high riffles of constant height throughout their length extending in the same direction as, of substantially greater 35 height than, and located at the high end of, the tapering riffles.

2. In an air separating table, a pervious deck, means for reciprocating it, means for discharging air upwardly through it, riffles 40 projecting upwardly from it, extending in the direction of reciprocation and decreasing in height from one end to the other, means for feeding material to be treated to the deck and a plurality of high riffles of constant 45 height throughout their length extending in the same direction as, of substantially greater height than, and located at the high end of, the tapering riffles, and terminating at a point intermediate the feeding means and 50 the discharge end of the deck.

3. In an air separating table, a pervious deck, means for reciprocating it, means for discharging air upwardly through it, riffles projecting upwardly from it, extending in 55 the direction of reciprocation and decreasing in height from one end to the other, means for feeding material to be treated to the deck and a plurality of high riffles of constant height throughout their length extending in 60 the same direction as, of substantially greater height than, and located at the high end of, the tapering riffles, and extending from the feeding end to a point short of the discharge 65 end of the deck.

4. In an air separating table, a pervious

deck, means for reciprocating it, means for discharging air upwardly through it, riffles projecting upwardly from it, extending in the direction of reciprocation and decreasing in height from one end to the other, means for feeding material to be treated to the deck and a plurality of high riffles of substantially greater height than, and located at the high end of, the tapering riffles.

5. In an air separating table, a pervious deck, means for reciprocating it, means for discharging air upwardly through it, riffles projecting upwardly from it, extending in the direction of reciprocation and decreasing in height from one end to the other, means for feeding material to be treated to the deck and a plurality of high riffles of constant height throughout their length extending in the same direction as, of substantially greater height than, and located at the high end of, the tapering riffles, the feeding means being located at one corner of the deck, the high riffles being located only on that side of the deck adjacent the feeding means.

6. In an air separating table, a pervious deck, means for reciprocating it, means for discharging air upwardly through it, riffles projecting upwardly from it, extending in the direction of reciprocation and decreasing in height from one end to the other, means for feeding material to be treated to the deck and a plurality of high riffles of constant height throughout their length extending in the same direction as, of substantially greater height than, and located at the high end of, the tapering riffles, the feeding means being located at one corner of the deck, the high riffles being located only on that side of the deck adjacent the feeding means, the high riffles furthest removed from the feeding means being substantially higher than any of the others.

7. In an air separating table, a pervious deck, means for discharging air upwardly through it, means for propelling a sheet of finely divided material across it, means immediately adjacent the deck and interposed between it and the air discharging means for resisting the flow of air toward it, said resisting means comprising a plurality of perforate plates spaced more closely together than the distance between the uppermost plate and the deck.

8. In an air separating table, a pervious deck, means for discharging air upwardly through it, means for propelling a sheet of finely divided material across it, and means independent of the deck for concentrating a part of the air flow and discharging it through the deck to give an area of increased air activity.

9. In an air separating table, a pervious deck, means for discharging air upwardly through it, means for propelling a sheet of

- finely divided material across it, and means independent of the deck for concentrating a part of the air flow and discharging it through the deck to give an area of increased air activity, riffles projecting upwardly from the deck and a plurality of high riffles in addition thereto located in line with the area of increased air activity. 5
10. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck. 10
11. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, a plurality of riffles projecting upwardly from the deck and riffles substantially higher than the remainder projecting upwardly from that part of the deck which is in register with the funnel. 15
20. 12. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, a plurality of riffles projecting upwardly from the deck and riffles substantially higher than the remainder projecting upwardly from that part of the deck which is in register with the funnel. 20
25. 13. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, means immediately adjacent the deck, interposed between it and the chimney, outside the funnel for resisting the flow of air toward the deck, manually adjusted shutters immediately beneath the deck adapted to be set to control the volume of air flowing through the deck. 30
30. 14. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, a plurality of riffles projecting upwardly from the deck and riffles substantially higher than the remainder projecting upwardly from that part of the deck which is in register with the funnel, means immediately adjacent the deck, interposed between it and the chimney, outside the funnel for resisting the flow of air toward the deck. 35
40. 15. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, a plurality of riffles projecting upwardly from the deck and riffles substantially higher than the remainder projecting upwardly from that part of the deck which is in register with the funnel, means immediately adjacent the deck, interposed between it and the chimney, outside the funnel for resisting the flow of air toward the deck. 40
45. 16. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, means immediately adjacent the deck, interposed between it and the chimney, outside the funnel for resisting the flow of air toward the deck, manually adjusted shutters immediately beneath the deck adapted to be set to control the volume of air flowing through the deck. 45
50. 17. In an air separating table, a pervious deck, means for propelling a sheet of finely divided material across it, an évasé chimney terminating at the deck and means for discharging air upwardly through it against the underside of the deck, a funnel located within the chimney, upwardly tapered and discharging against a portion of the deck, a plurality of riffles projecting upwardly from the deck and riffles substantially higher than the remainder projecting upwardly from that part of the deck which is in register with the funnel, means immediately adjacent the deck, interposed between it and the chimney, outside the funnel for resisting the flow of air toward the deck, manually adjusted shutters immediately beneath the deck adapted to be set to control the volume of air flowing through the deck. 50
55. 18. In an air separating table, a pervious deck, means for propelling a sheet of finely divided material across it, an évasé chimney terminating at the deck and means for discharging air upwardly through it against the underside of the deck, a conduit located within the chimney and adapted to receive air at a point therein intermediate the two ends of the chimney to discharge it upwardly against a portion of the deck. 55
60. 19. In an air separating table, a pervious deck, means for propelling a sheet of finely divided material across it, an évasé chimney 60

terminating at the deck and means for discharging air upwardly through it against the underside of the deck, a conduit located within the chimney and adapted to receive air at a point therein intermediate the two ends of the chimney to discharge it upwardly against a portion of the deck, a plurality of ruffles projecting upwardly from the deck and ruffles substantially higher than the remainder projecting upwardly from that part of the deck which is in register with the conduit.

20. In an air separating table, a pervious deck, means for propelling a sheet of finely divided material across it, an évasé chimney terminating at the deck and means for discharging air upwardly through it against the underside of the deck, a conduit located within the chimney and adapted to receive air at a point therein intermediate the two ends of the chimney to discharge it upwardly against a portion of the deck, means immediately adjacent the deck interposed between it and the chimney outside the conduit for resisting the flow of air toward the deck.

25. Signed at Chicago county of Cook and State of Illinois, this 26th day of January 1926.
